5 Claims. (Cl. 66—86)

Modern flat warp knitting machines have one or more positively driven warp beams which are arranged to rotate at such a speed that the warp threads are unwound from the warp beam at the same rate as that at which they are consumed at the knitting points. The speed at which the warp beam is rotated must be varied as the beams are emptied to allow for the reduction of, and small fluctuations in, the diameter of the warp threads on the beam so that the linear speed of the threads to the knitting points remains constant. The speed of rotation of the warp beam may be controlled by a warp let off mechanism of the kind in which a sensing device is rotated at a speed depending on the linear speed of the yarn threads leaving the warp beam and this speed of rotation is compared by some form of differential arrangement with that of a control member that is rotated at constant speed. The sensing device may be rotated by a rotary feeler such as a roller or a belt running on the surface of the warp threads or alternatively the sensing device may be a yarn disc which is rotated either by one of the warp threads from the warp beam or by a slave thread which is wound for example one and a half times around the warp beam before being knitted with the warp threads. As the speed of the sensing device increases or decreases, there is a relative rotation between the sensing device and the control member and this relative movement is used to close one of two electrical switches which correspond respectively to an increase and a decrease in the yarn speed. Closure of one of the switches operates a mechanism which adjusts the ratio of an infinitely variable speed gearing through which the warp beam is driven so that the linear speed of the thread returns to the required value at which the corresponding speed of rotation of the sensing device is equal to that of the control member. One example of this kind of warp let-off mechanism is described in our U.S. Patent No. 2,600,256.

The main disadvantage of this kind of system is that if the mechanism that adjusts the ratio of the gearing is sensitive enough to provide a quick correction to the warp beam speed, then there is the danger that before the appropriate switch has reopened, the system will have overcorrected and the sensing device and control member will have moved relatively to each other in the other sense sufficiently to close the other switch. The system will then correct and possibly overcorrect in the other direction. This leads to the production of hunting characteristics in the mechanism with consequent oscillation and chattering of the switch contacts which causes excessive wear of the parts.

According to the present invention a movement dependent on the correction of the ratio of the infinitely variable speed gearing is fed back to the two switches so that they are moved bodily in such a direction that the switch which had been closed as a result of relative movement between the sensing device and the control member tends to be reopened.

With this arrangement there is little danger of the system overcorrecting because the relative movement does not have to be reversed to open the switch and to prevent further correction taking place. Hunting is therefore

2

eliminated. However, if any overcorrection does take place, the sensing device and the control member do not have to pass back through their original relative datum position before the other switch is closed because both switches and correspondingly the datum position follow the relative movements of the sensing device and the control member. The system therefore settles to an equilibrium position very quickly.

The sensing device and the control member are preferably arranged to rotate two of the parts of an epicyclic gear or the two opposite input shafts of a differential gear so that an indicating member forming a third part of the gear only moves in one direction or the other to close one of the switches when the sensing device and the control member are rotated at different speeds. In order that the movement of the indicating member and the switches may be endless in either direction, they all preferably move in coaxial circles. A single correcting member which is moved in one direction or the other by an electric motor upon closure of one or other of the switches respectively may be arranged to vary both the ratio of the variable speed gearing and also to move the switches relatively to the indicating member.

One example of a flat warp knitting machine constructed in accordance with the present invention is illustrated in the accompanying drawings, in which:

FIGURE I is a diagrammatic end elevation of the machine;

FIGURE II is a side elevation of a warp let off control box;

FIGURE III is an end view of the box as seen in the direction of the arrow III in FIGURE II but with the end casing removed;

FIGURE IV is a section taken on the line IV—IV in FIGURE III;

FIGURE V is a section taken on the line V—V in FIGURE III; and

FIGURE VI is a section taken on the line VI—VI in FIGURE IV.

The machine has at each end a frame 1 with a bracket 2 which carries two warp beams 3 and 4. The warp sheet (not shown) from each warp beam passes over a tension bar (not shown) to the knitting point 5 where the fabric is knitted by the relative movements of the knitting elements 5a. The fabric passes from the knitting point 5 to a take-up roller 6 on which it is wound. The end thread 7 of each warp sheet is a slave thread which passes over a bar 8, one and a half times around a yarn disc 9, over a tension bar 10 and is consumed at the knitting point 5. Each yarn disc 9 comprises two circular plates 9a, 9b, connected by rubber covered pegs 9c. The yarn is wrapped on the pegs between the circular plates. Each disc is mounted at the top of a warp let off control box 11 which is carried by the bracket 2 and controls the speed of rotation of the corresponding warp beam.

In each warp let off control box 11 the yarn disc 9 is fixed to the hollow upper input shaft 12 of a differential gear 112, and rotates on lower input shaft 13 of the differential which forms the control member and is driven at constant speed from the main driving means of the machine. This drive is through a chain 14 in which drives a sprocket on an input shaft 15. At one end the input shaft 15 is mounted in a bearing 16 and at the other end it carries a gear wheel 17 which is in constant mesh through gear 17a with another gear wheel 18 mounted on a shaft 19 that is fixed to a driving cone 20. This cone 20 drives a second cone 21 by means of a ring 22 and forms an infinitely variable speed gearing of the type described in U.S. Patent No. 2,600,256. The ring 22 is moved between the cones 20 and 21 by means of a ring nut 23 which is threaded onto a lead screw 24. The lead

screw 24 is rotated by means of an operating knob 25 which carries a worm 27 in mesh with a worm wheel 28 on a rod 26 carrying an index dial 26a. The second cone 21 is fixed to a shaft 29 carrying a gear wheel 30 which is in constant mesh with another gear wheel 31 through an idler gear 32. The shafts 19 and 29 are parallel to the shaft 15, as best seen in FIG. VI. The gear wheel 31 is carried by a shaft 32a which also carries a worm 33 that meshes with a worm wheel 34 on the bottom of the input shaft 13. By rotating the operating knob 25 and altering the position of the ring 22 the ratio of the drive between the cones 20 and 21 may be altered in dependence upon the required warp let-off speed and the diameter of the warp beam. The input shaft 13 of the differential is therefore rotated at a constant speed which has been corrected by rotation of the operating knob 25 to meet these requirements.

The yarn disc 9 is rotated by the slave thread and drives the upper input shaft 12 and through it the upper input gear of the differential at a speed which is proportional to the linear speed of the warp sheet leaving the corresponding warp beam and this speed of rotation is compared with the rotational speed of the lower input member 13 in the differential lower input gear splined thereto. When the yarn disc and the lower input member 13 are rotated at the same speed planetary pinions 35 and 36, which are engaged between said upper and lower gears in the differential, rotate about their common axis but do not rotate about the axis of the shaft 13. The planetary pinion 36 carries a projecting indicating member 37 between two pairs of electrical wiping contacts 38 and 39 which are carried by the cage 40a of the differential. These pairs of contacts are separated by 15° around the circumference of the cage 40a. The two pairs of contacts 38 and 39 are connected one to each of two solenoids 40 and 41 respectively. The operation of one of the switches causes a clutch member 42 which is splined to the input shaft 13 to be moved upwards by a selector fork (not shown) into engagement with a bevel gear wheel 43 and closure of the other switch causes the clutch member to move downwards into engagement with a bevel gear wheel 44. These two bevel gear wheels 43 and 44 are in constant mesh in diametrically opposite positions with another bevel gear wheel 45 and are freely rotatable on the shaft 13. The gear wheel 45 is fixed to a shaft 46 which carries a pinion 47 in constant mesh with another pinion 48 on a second lead screw 49. This lead screw carries a ring nut 50 which moves a ring 51 that transmits drive between the second cone 21 and a third cone 52. This third cone 52 is fixed to a shaft 53 which carries a gear wheel 54 in constant mesh with a gear wheel 55 on a shaft 56. This shaft 56 carries a bevel gear wheel 57 in constant mesh with another bevel gear 58 on a vertical shaft 59 carrying a worm 60. The worm 60 is in mesh with a worm wheel 61 on an output shaft 62 which rotates the corresponding warp beam. The lead screw 49 is also profiled with a worm 63 which drives a worm wheel 64 connected to the bottom of the cage 40a of the differential.

Upon variation in the linear speed of the slave thread, the yarn disc and hence the input shaft 12 of the differential are rotated at a different speed than the other input shaft 13 of the differential. This causes the planetary pinion 36 to move around the axis of the shaft 13 until the indicating member 37 closes one of the pairs of wiping contacts 38 and 39. This causes solenoid 40 or 41 to be operated and in consequence the clutch member 42 is moved upwards or downwards into engagement with one of the bevel gear wheels 43 and 44. Depending on whether the slave thread is moving faster or slower than the desired speed a different one of the solenoids will be operated and the clutch member 42 will move into engagement with a different one of the bevel gear wheels 43 and 44. Depending on which of the bevel gear wheels 43 and 44 is rotated the shaft 46 and hence the lead screw 49 will be rotated in either one direction or

the other. This will move the ring nut 50 and hence the ring 51 in one direction or the other between the cones 21 and 52. The ratio of the gearing in the drive to the output shaft 62 is therefore varied.

When the indicating member 37 closes one of the pairs of wiping contacts 38 and 39 the resulting rotation of the lead screw 49 will cause the worm wheel 64 and hence the cage 40a to rotate in such a direction that the pair of wiping contacts which have been closed tend to move away from the indicating member 37 so that they are opened once more. If the correction in the speed of rotation of the warp beam is insufficient the indicating member 37 will follow the rotation of the cage 40a until the necessary variation in the ratio of the drive between the cones 21 and 52 has been accomplished. In the event of over correction the indicating member 37 will quickly engage the other pair of wiping contacts since the datum position of the indicating member between the pairs of wiping contacts has followed the movement of the indicating member. Any variation in the ratio of the drive between the cones 21 and 52 is therefore fed back to the cage 40a and the system quickly settles to a new equilibrium in which the yarn disc 9 is rotated by the slave thread at the same speed as the input shaft 13 is rotated.

One complete revolution of the cage 40a is equivalent to the full traverse of the ring 51 between the ends of the cones 21 and 52.

I claim:

1. In a flat warp knitting machine of the kind having a warp beam, power means for driving said warp beam, infinitely variable speed gearing operatively interposed between said power means and said warp beam, and a warp let-off mechanism controlling said infinitely variable speed gearing whereby said warp beam is rotated at a speed such that the linear speed of thread leaving the periphery of said warp beam is maintained substantially constant at a desired value; the improved warp let-off mechanism comprises, a rotary sensing device adapted to rotate at a speed corresponding to the linear speed of thread leaving the periphery of said warp beam, a rotary member adapted to be rotated at a constant speed corresponding to the desired linear speed of thread leaving said warp beam, movable actuating means respective to relative rotation between said sensing device and said rotary member, first switch means positioned to be closed upon movement of said actuating means in one direction following relative rotation between said sensing device and said sensing device and said rotary member in one sense and connected, when closed, to cause the ratio of said infinitely variable speed gearing to be increased, second switch means positioned to be closed upon movement of said actuating means in the other direction following relative rotation between said sensing device and said rotary member in the other sense and connected, when closed, to cause the ratio of said infinitely variable speed gearing to be decreased, means for moving said switch means bodily toward and away from said actuating means, and feed back means adapted to transmit back to said switch moving means a movement dependent on the correction to the ratio of said infinitely variable speed gearing whereby a switch means which has been closed as a result of relative rotation between said sensing device and said rotary member is moved away from said actuating means and reopens.

2. The invention according to claim 1, wherein said warp let-off mechanism includes a differential gear which has a first toothed gear rotatable with said sensing device, a second toothed gear rotatable with said rotary member, and said actuator means includes a part which meshes with said first and said second toothed gears.

3. The invention according to claim 1, wherein said feed back means comprises a single correcting member and an electric motor adapted to move said correcting member in one direction upon closure of said first switch means and to move said correcting member in the other direction upon closure of said second switch means, said

correcting member being adapted both to vary the ratio of said infinitely variable speed gearing and to move said first and second switch means relatively to said actuating means.

4. A flat warp knitting machine according to claim 1, comprising first and second infinitely variable cone drives interposed in series between said power means and said warp beam, said first cone drive being adapted to be set to a ratio corresponding to the required warp let-off speed and to the beam diameter and said second cone drive forming said infinitely variable speed gearing controlled by said warp let-off mechanism.

5. A machine according to claim 4, wherein the drive from said power means to said warp beam passes first

through said first cone drive, said rotary member of said warp let-off mechanism being driven at said constant speed by the second cone of said first cone drive.
